UNITED STATES PATENT OFFICE.

LEVI HAND, OF MINNEAPOLIS, MINNESOTA, ASSIGNOR OF ONE-HALF TO STEPHEN C. W. HALL, OF SIOUX FALLS, SOUTH DAKOTA, AND ONE-HALF TO ALFRED N. MUNSON, OF MINNEAPOLIS, MINNESOTA.

CHECK-MARKER.

1,221,049.

Specification of Letters Patent.

Patented Apr. 3, 1917.

Application filed May 25, 1916. Serial No. 99,889.

To all whom it may concern:

Be it known that I, LEVI HAND, a citizen of the United States, residing at Minneapolis, in the county of Hennepin and State 5 of Minnesota, have invented a new and useful Check-Marker, of which the following is a specification.

This invention relates to devices for marking bank checks and the like, one of its objects being to provide a simple and compact structure into which a check can be readily inserted and which can be quickly adjusted 10 to imprint selected characters thereon, novel means being provided whereby the check 15 can be fed longitudinally immediately subsequent to the operation of marking the same.

A further object is to provide a structure 20 of this character which is formed of but few parts and which will not easily get out of order.

With the foregoing and other objects in view which will appear as the description 25 proceeds, the invention resides in the combination and arrangement of parts and in the details of construction hereinafter described and claimed, it being understood that changes in the precise embodiment of the invention herein disclosed, can be made 30 within the scope of what is claimed, without departing from the spirit of the invention.

In the accompanying drawings the preferred form of the invention has been shown.

In said drawings:—

35 Figure 1 is a perspective view of the device.

Fig. 2 is a plan view thereof, the cover being in open position.

Fig. 3 is an enlarged vertical transverse 40 section through the device closed.

Fig. 4 is a vertical section through the device, said section being taken on the line A—B Fig. 3.

Fig. 5 is a vertical section through the 45 device, taken on line C—D Fig. 3.

Referring to the figures by characters of reference 1 designates a shallow casing provided at each end with a check receiving slot 2. Arranged upon the bottom of the 50 casing and extending transversely thereof near one end is a deflector 3 the top faces of which converge upwardly. In the apex of this deflector is a central opening 4 while at opposite sides of this central opening are

additional openings 5. A transverse shaft 6 55 extends under the deflector and close to the apex thereof and this shaft has any suitable means, such as a crank 7, whereby it can be rotated readily. Extending from the shaft is a lifting cam 8 designed to work within 60 the opening 4 and additional lifting cams 9 are also extended from the shaft and are designed to work within the openings 5. The cams 9 extend in a direction opposite to that in which the cam 8 extends and are disposed in alinement.

One of the openings 2 constitutes an inlet and extending from the bottom of the casing 1 close to this inlet is a tongue 10 the free end portion of which rests upon the deflector 70 3 and extends over the opening 4.

Arranged parallel with the tongue 10 and at opposite sides thereof are guide tongues 11 which extend from the top of the inlet opening 2 and rest upon the deflector 3 75 where they will cover the openings 5, the free ends of these tongues projecting through the outlet slot 2.

The casing 1 is provided with a cover 12 in which a pin 13 is mounted for rotation, 80 this pin being secured to and extending upwardly from the center of a disk 14 arranged close to and under the cover. On this disk and close to the periphery thereof are type indicated generally at 15 and which are designed to print different characters such as 1 to 9 inclusive, "0," "Pay \$," "cts," etc. An inking roller 16 is supported under the disk 14 and is adapted to be contacted by the type 15 as the disk 14 is rotated.

A dial or indicator 17 is provided upon the outer face of the cover and a pointer 18 moves thereover and is secured to and rotates with the pin 13. Thus when the pointer is directed to the numeral 8 on the 95 dial, the type which will print the number 8 will be in position above the free end portion of the tongue 10.

Cover 12 can be fastened in closed position by any suitable means, such as a spring 100 latch 19.

In using the device, free ends of tongues 11 are sprung upwardly and the check C to be marked is inserted end first through the inlet slot and will slide upwardly over the tongue 10 and under the tongues 11. It might be stated that these tongues 11 are secured to the wall of the casing at points above the

inlet opening so that ample clearance is provided for the reception of the check. The deflector 3 will serve as a means for directing the check upwardly over the shaft 6. The 5 tongues 11 extend downwardly along the deflector 3 and through the outlet opening 2 so that when the tongues are released after the check has been inserted said check will be held snugly upon the deflector by the 10 tongues 11. As soon as the check has been placed in proper position, the pointer 18 is rotated to indicate the first character to be printed. Shaft 6 is then rotated. During this rotation the cam 8 will first press upwardly against the tongue 10 and thus lift that portion of the check thereabove against the selected type, thereby to receive an impression therefrom. During the further rotation of the shaft in the same direction, cam 15 20 will move downwardly and away from the tongue 10, while the cams 9 move upwardly into the openings 5 and engage those portions of the check thereabove and pull the check longitudinally. The pointer 18 can 25 then be moved to the next character to be printed, thus bringing the selected type to active position whereupon another rotation of the shaft will cause the parts to operate as before described.

30 The tongues 11 are formed of thin strips of spring metal and the free ends projecting from the outlet openings can be easily raised so that the tongues will offer no resistance to the insertion of the check.

35 While the type 15 can be used for printing, it is also to be understood that the same can be used as perforating means and the claims are intended to cover a device which can either print or perforate.

40 What is claimed is:—

1. A device for marking checks, including a casing having opposed openings for the reception of a check, check deflecting means between the openings, resilient check holding means extending from one of the openings and bearing upon the deflecting means, a resilient lifting element bearing upon the deflecting means, a check being insertible between said lifting means and the holding 45 means, a marking element movable to position above the lifting element, and means for successively actuating the lifting element to

press a portion of a check against the marking element and to shift the check longitudinally.

2. A device for marking checks, including a casing having opposed openings for the reception of a check, check deflecting means between the openings, resilient check holding means extending from one of the openings and bearing upon the deflecting means, a resilient lifting element bearing upon the deflecting means, a check being insertible between said lifting means and the holding means, a marking element movable to position above the lifting element, means for successively actuating the lifting element to 55 press a portion of a check against the marking element and to shift the check longitudinally, said means including a shaft and lifting cams upon the shaft for engaging the lifting element and the check respectively. 60

3. Check marking means including a deflector, a lifting element bearing upon the deflector, means for holding a check over the lifting element and deflector and pressing said check upon the deflector, a marking element, means for moving said element to position above the lifting element, and means for actuating the lifting element to press a portion of the engaged check against the marking element. 70

4. Check marking means including a deflector, a lifting element bearing upon the deflector, means for holding a check over the lifting element and deflector and pressing said check upon the deflector, a marking element, means for moving said element to position above the lifting element, a shaft, oppositely extending projecting portions thereon, and means for rotating the shaft to bring said projecting portions successively 75 into engagement with the lifting element and the check, to successively press a portion of the check against the marking element and shift said check longitudinally. 80

In testimony that I claim the foregoing 85 as my own, I have hereto affixed my signature in the presence of two witnesses.

LEVI HAND.
